(57) **CLAIM**

The ornamental design for a display screen or portion thereof with icon as shown and described.

DESCRIPTION

1: Front

The COUNT STAR™ logo, forming part of the claimed design, is a trademark of Shanghai RuiYu Biotech Co., Ltd. The outer perimeter shown in a pair of broken lines in the drawings illustrates a display screen or portion thereof and forms no part of the claimed design; the dot-dash broken lines define the boundary of the claimed design and form no part of the claimed design.

1 Claim, 1 Drawing Sheet
